US00D898145S

(12) **United States Design Patent** (10) Patent No.: **US D898,145 S**
(45) Date of Patent: ** Oct. 6, 2020

(54) **GOLF CLUB HEAD**

(71) Applicant: **PARSONS XTREME GOLF, LLC**,
Scottsdale, AZ (US)

(72) Inventors: **Robert R. Parsons**, Scottsdale, AZ
(US); **Michael R. Nicolette**, Scottsdale,
AZ (US); **Bradley D. Schweigert**,
Anthem, AZ (US)

(73) Assignee: **PARSONS XTREME GOLF, LLC**,
Scottsdale, AZ (US)

(**) Term: **15 Years**

(21) Appl. No.: **29/689,669**

(22) Filed: **May 1, 2019**

Related U.S. Application Data

(60) Division of application No. 29/665,176, filed on Oct. 1, 2018, now Pat. No. Des. 852,302, which is a continuation-in-part of application No. 29/657,820, filed on Jul. 25, 2018, now abandoned.

CLAIM

The ornamental design for a golf club head, as shown and described.

DESCRIPTION

FIG. 1 is a top perspective view of a golf club head; FIG. 2 is a bottom perspective view of the golf club head of FIG. 1; FIG. 3 is a front elevational view of the golf club head of FIG. 1; FIG. 4 is a rear elevational view of the golf club head of FIG. 1; FIG. 5 is a top view of the golf club head of FIG. 1; FIG. 6 is a bottom view of the golf club head of FIG. 1; FIG. 7 is a left side view of the golf club head of FIG. 1; and, FIG. 8 is a right side view of the golf club head of FIG. 1. The broken lines show portions of the golf club head that form no part of the claimed design.

1 Claim, 8 Drawing Sheets
